[57] CLAIM

The ornamental design for an hand gun rack, as shown and described.

DESCRIPTION

FIG. 1 is a top, front, and right side perspective view of a hand gun rack showing my new design, the broken-line disclosure of a handgun being for illustrative purposes only and forms no part of the claimed design;

FIG. 2 is a top plan view thereof;

FIG. 3 is a front elevational view thereof;

FIG. 4 is a bottom plan view thereof;

FIG. 5 is a right side elevational view thereof, the left side

being a mirror image of that shown; and,

FIG. 6 is a rear elevational view thereof.
